Primary Examiner — Ania Aman(74) *Attorney, Agent, or Firm* — Cislo & Thomas, LLP(57) **CLAIM**

The ornamental design for a decorative cover for an engine air filter, as shown and described.

DESCRIPTION

FIG. 1 is a perspective view of an embodiment of my decorative cover for an engine air filter;

FIG. 2 is a first side elevation view thereof;

FIG. 3 is a second side elevation view opposite the first side elevation view;

FIG. 4 is a top plan view thereof;

FIG. 5 is a bottom plan view thereof;

FIG. 6 is a perspective view of another embodiment of my decorative cover for an engine air filter;

FIG. 7 is a first side elevation view thereof;

FIG. 8 is a second side elevation view opposite the first side elevation view;

FIG. 9 is a top plan view thereof; and,

FIG. 10 is a bottom plan view thereof.

The broken lines shown in the drawings illustrate portions of my decorative cover for an engine air filter that form no part of the claimed design.

1 Claim, 8 Drawing Sheets---
